UNITED STATES PATENT OFFICE.

THOMAS F. BENNETT, OF PHILADELPHIA, PENNSYLVANIA.

INCINERATING PLANT.

1,158,162.

Specification of Letters Patent. Patented Oct. 26, 1915.

Application filed June 6, 1914. Serial No. 843,431.

To all whom it may concern:

Be it known that I, THOMAS F. BENNETT, a citizen of the United States, residing in Philadelphia, Pennsylvania, have invented certain Improvements in Incinerating Plants, of which the following is a specification.

One object of my invention is to provide a novel form of furnace particularly designed for the incineration of garbage, sludge and other combustible materials, the various parts being so constructed and arranged that the apparatus is efficient under operating conditions, is substantial as well as convenient to operate, and is not likely to get out of repair nor require more than a minimum of attention.

A further object of my invention is to provide an incinerating plant having the above noted characteristics which shall be relatively inexpensive to construct and capable of being operated with a minimum of labor; it being also desired that the plant shall include novel means for causing the evaporation of liquid and also a novel arrangement of parts for receiving and preliminarily draining, and drying garbage and sludge as well as evaporating water.

These objects and other advantageous ends I secure as hereinafter set forth, reference being had to the accompanying drawings, in which:—

Figure 1 is a vertical section illustrating the detail construction of a plant constructed according to my invention, and Fig. 2 is a vertical section on the line *a—a* Fig. 1.

Referring to the above drawings, 1 represents a suitable foundation for the furnace proper and 2 the foundation for a stack 3 connected to said furnace as hereafter described. On the foundation 1 is erected the furnace setting which includes a back wall 4, a front wall 5 and side walls 6. The front wall extends upwardly to and terminates immediately under a dumping platform 7, having projecting forwardly from it a chamber forming a starting furnace 8 and an ash pit 9 separated by a grate 10, there being fire ash doors 11 and 12 provided for these two compartments. The bottom of the ash pit is preferably provided with a suitable concrete foundation or floor 13 ordinarily at a higher level than the foundation 1.

55 A vertical partition 15 extends transversely between the side walls 6 so as to pro-

vide a front or main furnace chamber 14 and a rear flue 16, the bottom of said chamber being formed by a hearth 17 inclined at a slight angle downwardly from the partition 15 to the rear end of the grate 10 where the rear of the starting furnace 8 opens into the main furnace so as to communicate directly with the lower front part thereof.

Spaced away from the hearth 17 though adjacent and immediately below the same is an evaporating hearth 18 preferably inclined in an opposite direction from the so-called garbage hearth 17 from the front to the rear of the furnace structure.

As shown in Fig. 2, I form in the partition 15 any desired and suitable number of vertical passages or slots 19 leading into the flue 16, there being in the present instance two sets of these so that the products of combustion and other gases arising from the chamber 14 are free to pass into said flue.

Elongated slots 20 or other suitably formed openings are also provided in the hearth 17, as well as in that part of the partition 15 between the two hearths 17 and 18, so that gases are free to pass through the former hearth into the space above the hearth 18 and thence into the flue 16.

At about the level of the hearth 18 I provide a horizontal partition 21 extending from one of the side walls 6 about half way toward the other and in the space under the hearth 18 and said horizontal partition I place a vertical baffle or partition 22 which extends from the rear wall 4 to within a short distance of the front wall 5. The flue 16 is thus continued through a flue 23 under the hearth 18 and thence through a second flue 24 also under said hearth and the partition 21, through the partition 15 and the rear wall 4 to the intake or bottom chamber 25 of the stack 3.

Above the flue 16 is mounted a receptacle 26 for the reception and temporary storage, draining, drying and evaporating of water in garbage and sludge to be incinerated and this is preferably formed of a metallic casting extending forwardly from the rear wall 4 for the entire width of the furnace and provided with one or more doors 27 hinged to its top portion and inclined downwardly and forwardly to within a short distance of the level of the dumping platform 7. In the present instance I have shown two of these doors, but obviously any desired num-

ber may be employed without departing from my invention.

From the back wall of the casing 26 the bottom 28 thereof is inclined downwardly and forwardly to the front face of the partition 15 and above this is mounted a more steeply inclined grate 28^a from the forward edge of which a gate 29 extends upwardly and forwardly to the level of the platform 7. This gate slides in suitable guideways and has a plurality of racks 43 mounted on its under face in position to be engaged by gear wheels 44 fixed to a transversely extending shaft 45 which may be driven from a hand wheel 46 through a vertically extending shaft 47 and suitable connecting gearing.

From opposite sides of the upper part of the casing 26 a conduit 34 extends downwardly to the upper part of the flue 16 so that any gases arising from the material in said casing when the furnace is in operation, are drawn from the upper portion thereof into the said flue and thence to the stack. The lower forward portion of the inclined bottom 28 has formed in it an elongated opening extending for the full width of the furnace and provided with a grating or screen 35 immediately above the top edge of the partition 15. The latter as well as the remainder of the furnace lining is preferably formed of fire brick or other refractory material and said partition has a series of vertical passages or ducts 36 leading from the space immediately under the grating to the rear ends of similar passages or ducts 37 formed in the hearth 17. At the forward ends of these latter passages are vertical passages 38 whose lower ends communicate with ducts or passages 39 in the bricks constituting the evaporating hearth 18 and the lower ends of these latter passages open directly into the flues 23 and 24. Both of the two sets of passages 37 and 39 preferably have clean-out openings and vents leading into them and the upper part of the incinerating chamber also has an opening 40 normally closed by a door 41 above the starting furnace 8, whereby access may be had to its interior when desired.

Under conditions of operation, the garbage to be incinerated is delivered onto the platform 7 and thence into the container 26 through the openings of the doors 27, the discharge gate 29 being in the closed position shown in Fig. 1. Previous to the placing of garbage in the casing 26, a fire is started in the furnace 8 on the grate 10 so that said furnace is thoroughly heated, as is also the combustion chamber or main furnace 14. Thereafter by opening the gate 29 to a suitable extent, the material in the casing 26 is allowed to fall or is drawn onto the hearth 17, it being noted, however, that previously a large proportion of the liquid

which is usually present passes through the grate 28^a and is directed by the inclined bottom 28 through the grating 35 into the upper ends of the conduits 36. Ordinarily this liquid would flow through and into the conduits 37, 38 and 39 but under operating conditions the hot gases from the fire in the furnace 8 and later those resulting from the intense combustion in the main furnace 14, heat the partition 15 and hearths 17 and 18 to such a high point, either directly or in passing through the flues 16, 23 and 24, that all of said liquid is completely evaporated before it can reach the lower end of the conduit 39. After the material on the hearth 17 has been heated by the hot gases from the furnace 8, to the point of ignition it is dragged forward onto the grate 10 in said furnace where it is mixed with coal or other fuel and its combustion is completed. This dried material is admitted to the hearth 17 as above described from time to time in any desired quantities, and is thereafter delivered to the starting furnace 8 where it is completely burnt.

Under the above noted conditions the hot products of combustion and other gases arising either from the furnace 8 or from the main combustion chamber 14, pass through the openings in the partition 15, into the flue 16 and with any gases which may be drawn from the upper part of the casing 26 through the conduit 34, pass downwardly into the flue 23, thence flowing forwardly and around the front of the partition 22 into the flue 24, from which they flow to the stack 3. Obviously these gases maintain both the partition 15 and the two hearths 17 and 18 at a high temperature, so that the liquid delivered from the casing 26 onto the plate 28 and into the passages 36, as well as that passing to the hearth 17, is evaporated. From time to time any ashes or other non-combustible material collecting on the hearth 17 or grate 10 may be drawn forward and removed through the fire door 11, although if desired the inclination of said hearth may be such that the ashes, etc., are automatically caused to flow into the furnace.

It is to be noted that I preferably so construct the gate 29 that its face within the combustion chamber of the main furnace 14 has a protective covering of asbestos or other refractory material, thereby effectually preventing injury from the high temperature in said chamber.

As shown in Fig. 1, the bottom chamber 25 of the stack has the general form of the top of a bottle, being provided with a relatively narrow neck where it enters the main chamber of said stack. My object in providing this construction is to set up a whirling motion of the gases coming from the conduit 24, so that any sparks or heavy in-

candescent particles will be deposited before the gases pass into and out of the stack proper.

The passages or ducts 36, 37, 38, and 39 are preferably formed by metal pipes mounted in a suitable manner within the refractory walls or hearths 15, 17 and 18.

I claim:—

1. The combination in an incinerating plant of a furnace; and a receiving casing mounted above said furnace in position to discharge thereinto, there being a conduit extending vertically through a side wall of the furnace so as to be heated by the products of combustion and connected to receive liquid flowing from the receiving casing.

2. The combination in an incinerating plant of a furnace having a vertical wall including conduits extending longitudinally therethrough; a hearth having conduits therein connected to the passages of the wall; with a receiving casing mounted to discharge solid material into the furnace and having a liquid outlet connected to deliver to the passages in the wall.

3. The combination in an incinerating plant of a furnace having a hearth and a wall provided with connecting passages; an evaporating hearth having passages connected with the passages of said first hearth; with a receiving casing mounted to deliver into the furnace and provided with a liquid outlet discharging into the passages in the furnace wall.

4. The combination in an incinerating plant of an inclosing structure; a furnace therein; a wall for the furnace coöperating with said structure to form a vertically extending flue immediately adjacent said furnace and having passages therein; said wall being provided with openings connecting the

flue and the furnace; a receiving casing having an inclined bottom over the flue and provided with a liquid outlet at its lower end draining into the passages in the wall; 45 and a gate for controlling the passage of material from the casing into the furnace.

5. The combination in an incinerating plant of a base and walls forming a setting; a partition dividing the chamber formed by 50 said setting into a furnace and a flue and provided with openings and liquid receiving conduits; a stack connected to said flue; a receiving casing having an inclined bottom over the flue and arranged to deliver liquid 55 into the conduits of the partition; with an inclined door for the casing slidably mounted in the setting and co-acting with the lower edge of said bottom when in its closed position.

6. The combination in an incinerating plant of a base and walls forming a setting; a partition having openings therethrough and dividing the chamber formed by said setting into a furnace and a flue, a stack 65 connected to the flue; a receiving casing having an inclined bottom over the flue; and an inclined door for the casing slidably mounted in the setting and co-acting with the lower edge of said bottom when in its closed position, said furnace having a hearth provided with passages and the partition likewise having passages connecting with those of the hearth and connected with the lower part of the receiving casing.

In testimony whereof, I have signed my name to this specification, in the presence of two subscribing witnesses.

THOMAS F. BENNETT.
